HOOP

Ralph G. Hiers and Ralph H. Hiers, Granville,
Mass., assignors to Noble & Cooley Co., Gran-
ville, Mass., a corporation of Massachusetts

Application June 20, 1933, Serial No. 676,614

4 Claims. (Cl. 272—85)

The commercial production of playing hoops for children has long been attended by considerable difficulty. The hoops of the market have been divided into two classes, those of good quality selling at retail at about one dollar, and the cheaper hoops intended for distribution in the 5 & 10¢ stores. These latter hoops have been unsatisfactory in their resilience, strength, and ability to preserve their shape. No satisfactory way of bridging the gap between the high priced hoops and the unsatisfactory ones sold at cheap prices has hitherto been found.

In accordance with the present invention a hoop may be constructed at a sufficiently low cost to permit retailing in low or medium priced stores, with a quality substantially equal to that possessed by the former higher priced articles. In particular a hoop construction in accordance with this invention will keep its truly circular shape much longer than any low priced hoop heretofore made. The hoops constructed in accordance with this invention are likewise more readily controlled in their elasticity than has heretofore been possible. In addition to these features, the improved hoops lend themselves to particularly distinctive decoration at a low cost.

The invention will now be described in connection with the accompanying drawing, in which:

Fig. 1 is a perspective view of a hoop constructed in accordance with the invention;
Fig. 2 is a section on line 2—2 of Fig. 1; and
Fig. 3 is a perspective detail on an enlarged scale of a fragment of the inner periphery of the hoop.
The body of the hoop is made up of a metal annulus 10 having its sides 11 formed in generally channel shape open toward the inside of the hoop and rolled over or incurved as at 12, so as to avoid the presence of sharp corners. This construction also gives a substantial lateral and circumferential stability to the hoop. Within the channel is placed an annular filler 13 which is preferably formed of wood or other material which adds to the resilience of the complete hoop. This filler is held in position by the incurved sides 12 of the channel. The filler may be made as a single complete annulus or may be made in sections; the latter construction being substantially less expensive where the filler is made of wood. Due to the reciprocal reinforcing effect of the metal and wood, the resilient qualities of the hoop are not substantially different whether a single or a sectional filler is used.

It is preferable for several reasons, of which the main one is economy in manufacture, to form

the annulus 10 of a plurality of segments having one end of each section reduced in size, as at 14, so as to telescope within the end of the adjacent section. This segmental method of forming the annulus permits the channel sections to be formed by a punching operation much more readily than were a complete annulus to be made. It has the further advantage that the several segments may be made of strips of metal which may be lacquered or otherwise colored while in flat form, thus permitting a division of the hoop into segments of different color without the necessity of subjecting the complete hoop to any delicate painting operation.

What we claim is:

1. A child's rolling hoop comprising a segmental annulus of metal, channel formed in cross-section and with incurved edges, the ends of the segments being telescoped together, and a filler located in the channel and held in place by said incurved edges.

2. A child's rolling hoop comprising a metal annulus, channel formed towards its inner periphery, and having the edges of the channel curved inwardly and towards each other to form smooth edges and to give lateral and circumferential stability to the annulus and finally curved towards the body of the annulus to reinforce it and to control its resilience.

3. A child's rolling hoop comprising a metal annulus, channel formed towards its inner periphery, and having the edges of the channel incurved to form smooth edges and to give lateral and circumferential stability to the annulus, and a filler extending around the channel and held in place by the incurved edges thereof.

4. A child's rolling hoop comprising a segmental annulus of metal, channel formed in cross section and with incurved edges, the ends of the segments being telescoped together, and a filler of resilient wood located in the channel and held in place by said incurved edges.
